COMBINED MOWER, CONDITIONER, AND WINDROWER

Donald E. Burrough and Theodore M. Barnes, Ottumwa, Iowa, assignors to Deere & Company, Moline, Ill., a corporation of Delaware

Filed Sept. 15, 1966, Ser. No. 3,871

Term of patent 14 years

(Cl. D40—1)

FIG. 1

FIG. 2

FIG. 1 is a left front perspective view of a combined mower, conditioner, and windrower embodying our new design.

FIG. 2 is a right front perspective thereof.

FIG. 3 is a left rear perspective view with portions of the hitch fragmentarily shown for ease of illustration.

FIG. 4 is a right rear perspective thereof.

We claim:

The ornamental design for a combined mower, conditioner, and windrower, substantially as shown and described.
